UNITED STATES PATENT OFFICE

LEOPOLD KACZANDER, OF NEW YORK, N. Y., ASSIGNOR TO NATHAN
MANUFACTURING COMPANY, OF NEW YORK, N. Y.

MULTIPLE DROP-FEED APPARATUS FOR LIQUIDS.

No. 823,223.

Specification of Letters Patent.

Patented June 12, 1906.

Application filed March 6, 1906. Serial No. 304,537.

To all whom it may concern:

Be it known that I, LEOPOLD KACZANDER, a citizen of the United States, residing in the city of New York, county and State of New York, have invented certain new and useful Improvements in Multiple Drop-Feed Apparatus for Liquids, of which the following is a specification.

My invention relates to drop-feed apparatus for liquids, and more particularly to that kind of such apparatus in which two or more liquids of different specific gravities or of otherwise different characteristics are contained each in its own chamber and are fed therefrom each independently of the other in measured or determinate quantity, and preferably in visible drops. Such an apparatus is useful in a variety of connections—for example, as an oiler to feed lubricants of different kinds to engines in cases where one kind of lubricant is required for the cylinder and another kind for the bearings, as an instrument in surgery for the administration of different kinds of anesthetics, &c.

The object of the invention is to make such apparatus simple and compact in construction and efficient in operation; and the main characteristic of the invention is that the apparatus comprises separate and distinct superposed vessels or chambers for holding the different liquids, the vessel above discharging its contents through a conduit which passes through, but does not communicate with, the vessel or vessels below.

The invention will first be described in its structural details in connection with the accompanying drawings, forming part of this specification, and will then be more particularly pointed out in the claim.

In the drawings, Figure 1 is a vertical axial section of the apparatus in its preferred form. Fig. 2 is a like section, partly in elevation, of a modification. Fig. 3 is a like section, in a plane at right angles to the plane of section in Fig. 1, of still another modification.

Similar letters of reference indicate corresponding parts in all the figures.

A is the body of a vessel of any suitable form, preferably of cylinder shape, and of any suitable material, preferably glass, provided at the lower end with a metallic bottom piece B, in which the glass sits, a cork washer C or a washer of other suitable mate-

rial being interposed between the glass and the metallic bottom B. At its upper end the glass body A is provided with a metallic cap D and with another interposed washer E to make a tight joint between the top of the glass and its metallic cap. The cap is provided with an opening F. The opening F is closed by means of a damper in the shape of a screw-threaded cap G, which screws upon a like screw-threaded part of the cap D and is provided with an opening H. When cap G is turned so that the two openings F and H register, the fluid to be contained in the vessel A may be poured in through these openings. When, on the other hand, the cap G is rotated sufficiently to throw the opening H out of register with opening F, the latter will be covered by the blank surface of cap G and the vessel A will be closed.

In the center of the bottom piece B is screwed a tube I, which passes through the glass A and the caps D and G. The protruding upper end of the tube is threaded for the reception of a lock-nut K. By screwing this lock-nut against the projecting nipple L of cap D the bottom B and the cap D will be drawn tight against the washers at the top and bottom of the glass A, and a fluid-tight joint will be made at those points. It will be noted that there is no communication between the tube I and the vessel A—that is, nothing can pass from the tube I into vessel A or from this vessel into tube I.

Into the sides of bottom B are screwed the chambers M, having direct communication with the interior of vessel A. These chambers are provided with drop-nipples N, and to them are attached the sight-chambers O, provided with openings P and glass tubes R, through which the drops of fluid as they descend from nipples N may be observed. These devices are quite similar to the sight-feed glasses of the conventional locomotive-lubricator type. The regulation of the rate of feed is accomplished by means of a pointed spindle S, usual in such sight-feed devices. To the spindle is attached the lever T, which when up, as on the right side of the apparatus in Fig. 1, opens an outlet at the bottom of chamber M at U, the fluid passing from chamber A, through passages V and U, into the glass R and through the final drop-nipple w to its destination. When the lever T is "down," as on the left side

of the figure, the feed stops. The regulation is effected by moving the nut X up or down the threaded neck of chamber M. When nut X is moved upward, the tension of the 5 spring Y is relaxed and the spindle S will move upward with nut X. When nut X is moved downward, the spring Y is compressed and presses against the collar Z of spindle S, pressing the latter downward.

10 To the top of tube I is secured the metallic bottom b of a second glass vessel a, provided also with an upper metallic cap d, containing an opening f. A rotating cap g (similar to the cap G, already described) with an opening h in it opens or closes a filler-opening, according as these openings f and h register or not. The fluid-tight joint between glass a and its metallic base and top is made by screwing the lock-nut k tight against the 15 nipple l of cap g, which tightens the glass on the cork washers c and e in similar manner as already described with reference to the lower glass A. A tube j, screwed into the metallic base b, passes through glass a and 20 caps d and g, which tube is provided with an opening v, through which the fluid from vessel a passes to a valve-controlled opening u in the base b, which communicates with the tube I. The valve which controls the opening 25 u is part of a spindle s, to which is attached lever t, which, in conjunction with nut x and spring y, effects the regulation of the rate of speed from vessel a in the same manner as do the regulating-valves for vessel 30 35 A, already described. The fluid from vessel a passes down through tube j and opening u into tube I, and down through that tube to a nipple n in the bottom B, and from that nipple through a sight-glass r, and finally 40 through nipple w to its destination. Manifestly there is no communication whatever in this construction between the lower vessel and the tube I, which serves as a conduit to carry off the contents of the upper vessel.

45 It is evident that changes in the construction of this apparatus may be made without departing from the nature of the invention. For example, the regulating apparatus of the upper vessel a may be dispensed with and 50 the lower end of tube I may communicate with a T-fitting B', screwed into the bottom B, as shown in Fig. 3, into the ends of which

T-fitting chambers M', similar to chambers M, Fig. 1, may be screwed, each being provided with the regulating feature already 55 described for its feed-outlet. In this case the vessel a will simply serve as a reservoir to supply with fluid the chambers M'. The bottom B of the chamber A is provided with drop-nipples w (one of which is indicated in 60 Fig. 3) and devices connecting the same to said bottom similar in function and purpose to those already described in connection with Fig. 1. It is also evident that additional chambers may be added to chambers 65 M, as well as M', if more than two outlets are to be fed from either of the vessels A and a. Such modification for the lower vessel A is shown in Fig. 2, M² representing additional chambers attached to chambers 70 M, forming four feed-outlets from vessel A.

In all of these forms of apparatus it will be noticed that the vessels are superposed and that the conduit for the discharge of the contents of the upper vessel while it passes 75 through has no communication whatever with the interior of the lower vessel, the contents of the vessels being thus kept wholly separate from each other.

Having described my improvements and 80 the best way now known to me of carrying the same into practical effect, I state, in conclusion, that I do not limit myself to the structural details herein illustrated, since manifestly the same can be considerably 85 varied without departure from the spirit of my invention; but

What I claim herein as new, and desire to secure by Letters Patent, is as follows:

In a multiple drop-feed apparatus, a plurality of distinct and separate non-communicating superposed liquid-containing vessels, a discharge-tube leading from the upper vessel down through the lower vessel, separate and distinct feed devices for the 90 contents of each vessel, and regulating-valves for the several feeds, substantially as hereinbefore set forth.

In testimony whereof I affix my signature in presence of two witnesses.

LEOPOLD KACZANDER.
